UNITED STATES PATENT OFFICE.

ROLLIN SMITH HURLBUT, OF ONEIDA, NEW YORK, ASSIGNOR TO ONEIDA COMMUNITY, LIMITED, OF ONEIDA, NEW YORK, A CORPORATION OF NEW YORK.

ANIMAL-TRAP.

1,238,019.

Specification of Letters Patent. Patented Aug. 21, 1917.

Application filed February 6, 1917. Serial No. 146,900.

To all whom it may concern:

Be it known that I, ROLLIN SMITH HURLBUT, a citizen of the United States of America, and resident of Oneida, in the county of Madison, in the State of New York, have invented new and useful Improvements in Animal-Traps, of which the following, taken in connection with the accompanying drawings, is a full, clear, and exact description.

This invention relates to certain improvements in animal traps, involving the use of a pair of jaws, an actuating spring therefor and suitable means for setting the jaws against the action of said spring.

In traps of this character, the springs are usually secured to the base in such a manner as to cause an abrupt termination of the action at a single point—generally at the point of securement to the base,—with the result that the fulcrum is changed when the trap's spring is under tension, shortening the same, and thereby increasing the liability to breakage.

The main object of my invention is to obviate this difficulty not only by making the spring and jaw-operating tongue of a single piece of spring metal, but also by connecting these parts at their junctions one with the other through the medium of an open loop, the opposite portions of which are spaced apart at all points so that it may readily yield at all points throughout the length of the loop instead of at any one particular point,—that is, the entire spring tongue, together with the loop and adjacent end of the base, are free to flex at all points throughout their lengths.

Another object is to hinge the jaws at one end to the corresponding end of the base and at the opposite end to the inner side of the loop apart from the outer side of the loop so as to preserve the resiliency of the loop throughout its length and allow both the inner and outer sides of the loop to move freely relatively to each other as the spring tongue is set and released.

Other objects and uses relating to specific parts of the trap will be brought out in the following description.

In the drawings—

Figure 1 is a top plan of an animal trap

embodying the features of my invention, the parts being shown as "set."

Fig. 2 is a side elevation, partly in section, of the same trap, in which the parts are sprung or in their closed positions.

Fig. 3 is a plan of the detached blank forming the base and spring tongue.

As illustrated, this trap comprises a base —1— and an overlying spring tongue —2— made of a single piece of spring metal integrally united at one end through the medium of an open loop —3— which is returned upwardly from one end of the base 65 toward the opposite end and then downwardly toward the main body of the base and deflected longitudinally over the main body of said base to form the main body of the jaw-operating tongue.

The end of the base —1— opposite the loop is provided with an upturned flange or ear —4— having suitable apertures —5— for receiving the pintles —6— on one end of a pair of jaws —7—, the corresponding end of the spring tongue —2— being provided with longitudinal elongated openings —8— for receiving the adjacent ends of the jaws and ear —4—.

The opposite ends of the jaws are provided with similar pintles —6— journaled in apertures —5— in the inner side of the loop —3— apart from the outer side of said loop so as to preserve the resiliency of all portions of said loop throughout its length.

The integral connections between the main bodies of the base —1— and spring tongue —2— constitute a compound or reverse curve, of which the loop —3— forms a part, all of the curved portions of this connection being of sufficiently long radius to allow such portions to flex freely at all points throughout their lengths as the spring tongue is brought under tension, thus avoiding any abrupt termination of vibrations at any part of the connection between the spring tongue and base which not only increases the resiliency of the spring, but also maintains such resiliency for a longer period of time and greatly increases the period of efficiency and life of the trap.

Any suitable means may be provided for setting the trap, said means consisting, in this instance, of a platform —9— suitably

hinged to a cross bar —10— on the central portion of the base and provided with a pivoted detent —11— for interlocking engagement in the usual manner with one of the jaws and a suitable shoulder —12— on the heel of the platform so that when the trap is set, the free end of the spring tongue —2— will be depressed to the position shown by dotted lines in Fig. 2 below the plane of the pintles —6— out of contact with the jaws —9—, while on the other hand when the platform is tripped and the spring released, the latter will quickly and automatically assume the position shown by full lines in Fig. 2 to close the jaws.

Another advantage in joining the spring tongue to the base through the medium of an open loop is that the loop may be used as a means of attachment for a swivel or other connection by which the trap may be attached to a fixed anchorage, the swivel being merely hooked or drawn through the loop —3— without in any way interfering with the free operation of the jaws or resilient action of all portions of the loop throughout its length.

What I claim is:

1. In an animal trap of the character described, a one-piece base and jaw-operating spring forming at their junction an open loop, in combination with jaws journaled at one end on the corresponding end of the base and at their opposite end on the inner side of the loop apart from the outer side of said loop, and means for holding the spring in compressed condition.

2. In an animal trap of the character described, the combination of a base and an overlying jaw-operating tongue, both made of spring metal and integrally united at one end by an open loop, opposite portions of which are in spaced relation to allow all portions thereof to yield under the action of the tongue, jaws hinged at one end to the corresponding end of the base and having their opposite ends hinged to the inner side of the loop apart from the outer side of said

loop to allow relative spring movement of both inner and outer sides of the loop, and means for holding the spring in a compressed condition.

3. A trap comprising a one-piece base and jaw-operating spring formed with an intermediate curved loop, and jaws, each having one of their ends journaled in one side of the loops.

4. An animal trap comprising a one-piece base and jaw-operating spring formed with an intermediate curved loop, and jaws having pintles upon their opposite ends, the pintles on one end journaled on the base, and the pintles on the other end journaled in one side of the loop only.

5. An animal trap comprising a base and spring integrally united at one end by a curved loop, a substantially vertically extending flange upon the end of the base, said loop having substantially vertically extending spaced portions, and jaws having pintles journaled in the base flange and the adjacent vertical portion only of the loop.

6. A trap comprising a base and spring integrally united by an arcuate open loop including a return-bent portion extending toward the base, and jaws having pintles journaled in the return-bent portion of the loop.

7. An animal trap comprising a substantially horizontal base, a spring lying above the base, the spring and base connected by an open loop including a substantially vertical portion, jaws having pintles upon their opposite ends, the pintles on one end being journaled in the substantially vertical portion of the loop and the pintles on the other end journaled on the base, and means for holding the spring in compressed condition.

In witness whereof I have hereunto set my hand this 26th day of January, 1917.

ROLLIN SMITH HURLBUT.
